INVENTOR.

J. Madison Thorp,

UNITED STATES PATENT OFFICE.

JAMES MADISON THORP, OF ALAMEDA, CALIFORNIA.

EXPLOSION OIL-ENGINE.

1,247,904.

Specification of Letters Patent. Patented Nov. 27, 1917.

Application filed April 9, 1917. Serial No. 160,784.

To all whom it may concern:

Be it known that I, JAMES MADISON THORP, a citizen of the United States, residing at Alameda, in the county of Alameda and State of California, have invented 5 certain new and useful Improvements in Explosion Oil-Engines, of which the following is a specification.

My invention relates to explosion engines 10 using heavy oil for fuel, and the objects of my invention are to utilize low-grade fuel oil in engines of moderate compression pressures and to obtain high speed in the engine while operating on such fuel.

Methods of combustion employed heretofore in low-grade-oil engines produce slow 15 piston speed because of slow burning of the fuel, the oil injected into the compressed air in the cylinder will not gasify rapidly enough to cause explosion of the charge. An engine to run at high speed must be 20 operated on fuel that will explode, rather than a slow burning fuel. And since low-grade fuel oils in high speed engines will 25 not gasify during the time allowed between injection of the fuel and ignition of the charge such fuel then must be gasified before it enters the combustion chamber. Therefore another object of the invention is 30 to provide a method whereby such fuel may have a time equal to one or more complete cycles of the engine to be converted into gas, then to allow the gas thus produced to enter the combustion chamber and mix with 35 the air being compressed by the piston, then to ignite and explode the combustible charge thus obtained.

With these and other objects in view I 40 will proceed to describe a method and apparatus embodying my invention, reference being had to the accompanying drawings, in which similar characters of reference denote similar parts throughout the several views.

Figure 1 is a vertical section of the engine 45 through C D of Fig. 2; Fig. 2 a cross section through A B of Fig. 1; and Fig. 3 a diagram showing positions of the valve movements relative to the piston stroke, the 50 arrow shows direction of crank rotation.

The cylinder E and piston F are that of 55 the ordinary two-stroke cycle engine, the invention lies wholly in the arrangements in and upon the cylinder head, where I have shown a water-cooled cylinder head 1, inclosing a retort 1^a, composed of a com-

paratively long passage with the conical rotary valve 2 connecting alternately with either end of the passage as at 3 and 4 respectively. 5 and 6 are nozzles to supply 60 the retort with oil fuel and water. 7 is a shaft ordinarily geared to the engine crank shaft and is designed to operate the gear 8 and through the gears 9 and 10 to rotate the valve 2; 11 is the usual spark plug which 65 reaches through to the combustion chamber of the cylinder, the spark gap is at 12. The valve 2 is provided with water-cooling space which communicates with the cylinder head water through the ports 13 Fig. 1 and as 70 shown in dotted lines 13 14 in Fig. 2. Other and obvious parts usually applied to engines of this character are omitted in the drawing.

In operation:

Assuming the engine to have received its 75 initial charge which has been exploded and the piston started on the power stroke to the position 15 Figs. 1 and 3, at which point the valve 2 begins to open, going through the movement of opening and closing while 80 the piston travels from 15 to 16 in the diagram, during which time communication is open at port 3 between the cylinder and the retort allowing a portion of the hot burnt gases to enter the retort, compressing the 85 contents thereof toward the opposite end of the passage, then as the cylinder gases are expanding on the power stroke the retort contents will expand also and gradually 90 force a portion back into the cylinder, 95 equalizing the pressure until the valve cuts off communication at piston position 16, after which the fuel and water is injected into the retort through the nozzles, 5 and 6 respectively, by means of the usual injector pump, not shown. The piston continues its 100 cycle including the power stroke to the point of exhaust, air intake and the compression stroke to the point 17 in the diagram where the valve begins to open the port 4 at the other end of the retort passage, opening and closing while the piston moves from 17 to 18, during which time a portion of the retort 105 contents, composed of the oil, water and burnt gases, and now completely gasified, 110 will eject itself from the retort into the air being compressed in the cylinder and commingle therewith until the pressure in cylinder and retort is equalized and the valve closes at 18. Then as the piston continues upward with all valve communication closed the cylinder charge is fired by the spark,

as indicated in the diagram, causing explosion of the charge with the usual rise in pressure and temperature, and another cycle begins as described above.

- 5 During the operation of gas injection into the cylinder, as described, it will be noted that at the opening of the valve at piston position 17 in the diagram, the air pressure is constantly rising while the higher retort pressure is suddenly released into the air, the two being equalized by the time the valve is full open, then as the compression pressure continues to rise some of the gas and air will be forced back into
- 10 the retort, until the valve closes at 18, causing a churning effect that reaches throughout the retort passage. The same effect is had at the opposite end of the passage by the entrance and back flow of the burnt gases,
- 15 20 this churning greatly assists in breaking up the gas constituents.

It will be seen that this method allows time equal to more than one cycle of the engine to gasify the fuel, a small quantity of fuel and burnt gas entering one end of the retort, being gradually forced toward the opposite end, as shown by the arrows, gasifying as it travels through the long passage and finally ejecting a portion of the retort contents from the other end at each cycle of the engine.

It will be noted also that the gas charge enters the cylinder at about three-fourth compression stroke when the compressing air is comparatively hot, thus avoiding condensation of the gas.

I have shown the invention as applied to a two-stroke cycle engine, I do not, however, confine myself to engines of any particular cycle, as the method is applicable to practically all engines, working on the internal combustion principle, without change in the invention, timing of the valve to suit the cycle being the only change necessary.

I prefer to inject the fuel at the time in the cycle described, the time may be varied considerable, however, without reducing the efficiency of the method.

50 I have also described the method as using water with the fuel, yet I do not confine myself to its use. Although water or steam is found to be beneficial it is not absolutely necessary to the working of the method. 55 It is further obvious that changes may be made in the mechanism without departing from the spirit of the invention, such for example, as substituting two puppet valves for the one rotary valve shown, and by changing the shape of the retort passage, therefore I do not confine myself to the exact construction herein shown.

With this method the amount of air taken into the cylinder at each cycle is constant, 60 65 the regulation being accomplished by vary-

ing the fuel supply together with variable spark timing. However, in engines designed for great flexibility in speed and load the valve time may be varied also, for example, assuming that the fuel has been cut down to a minimum, now if this small quantity of gas were admitted to the cylinder very early in the compression stroke so that it would have time to thoroughly mix with the full charge of air, such mixture would be too poor to explode, on the other hand to retard the valve time so that the gas enters near the end of the compression stroke it will then—before being fired—have time only to mix with the air nearest the inlet, that is, a smaller quantity of air, leaving the mixture much richer and explodable giving a full strength explosion of small volume.

In engines designed to use a more volatile fuel the retort passage may be shortened so that the fuel may have a time equal to only one cycle, or less, of the engine to gasify.

Having thus clearly described my invention, what I claim as new and desire to secure by Letters Patent is—

1. In an explosion engine, the method of gasifying fuel, consisting of injecting fuel into a retort, then allowing a part of the products of combustion in an engine cylinder to enter one end of the passage of said retort, then closing said end of the passage, then opening the other end of said retort passage and allowing some of the gasified contents of the retort to enter said cylinder during compression of the air therein, whereby said gasified fuel is commingled with said air to form an explosive charge.

2. In an explosion engine, the method of gasifying fuel, consisting of allowing some of the products of combustion in an engine cylinder to enter one end of a retort, then closing said end of the retort, then injecting fuel into said retort, then opening the other end of the retort and allowing some of the gasified contents of said retort to enter and carburize a charge of air being compressed in said cylinder, then igniting said carburized charge.

3. In an explosion engine, the method of gasifying fuel, consisting of allowing some of the products of combustion in an engine cylinder to enter one end of a retort, then closing said end of the retort, then injecting fuel oil and water or steam into the retort, then opening the other end of the retort to allow a portion of the contents thereof to enter and carburize a charge of air in said cylinder.

4. In an explosion engine, the method of gasifying fuel, where a portion of the burnt gas in an engine cylinder is forced into a retort passage at one end thereof, fuel injected into said retort at or near said end,

then repeating the foregoing steps so that the first portion of burnt gas and fuel is forced along said passage by the second portion of burnt gas whereby said first portion 5 remains in the retort for a time longer than one cycle of the engine, then allowing said first portion of fuel and burnt gas to be ejected into the cylinder to carburize the charge of air compressed therein.

10 5. In an explosion engine, a retort in the

cylinder head, consisting of a long passage or conduit with valved ends communicating with the engine cylinder, means for opening and closing one end of said passage during the power stroke of the engine, means 15 for injecting fuel into the retort, and means for opening and closing the other end of the retort during the compression stroke, for the purpose specified.

J. MADISON THORP.
